WITNESS:

Patented Apr. 29, 1924.

UNITED STATES PATENT OFFICE.

CHARLES H. BEAR, OF YORK, PENNSYLVANIA.

BURNER.

Application filed September 1, 1922. Serial No. 585,742.

To all whom it may concern:

Be it known that I, CHARLES H. BEAR, a citizen of the United States, residing at York, in the county of York and State of Pennsylvania, have invented new and useful Improvements in Burners, of which the following is a specification.

This invention relates to an oil burner for furnaces, stoves and the like, the general object of the invention being to provide a burner which will burn low grade fuel with great efficiency.

This invention also consists in certain other features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is an enlarged sectional view through the burner bowl.

Figure 2 is a plan view of the burner bowl.

Referring now to the drawing there is shown the present preferred embodiment. The burner bowl is shown at 6, and said bowl is formed with the nozzle 7, the passage 8 of angle shape which communicates with the top of the outer end of the nozzle, the passage 9 for the pilot flame fuel and the flange 10 which forms a chamber to receive the absorbent material 11 which is saturated with the fuel coming through the passage 9. The bowl is of the shape shown and a perforated baffle plate 12 is supported above the opening therein by means of a post 14. The bowl has upwardly and outwardly curved walls to form a bowl of substantially cup-shape with an inwardly extending flange at its top. A portion of the wall is flat and this portion has the nozzle formed thereon. The fuel is conducted through pipe 15 to the nozzle chamber 8 of the burner, and also through pipe 16 to the pilot passage 9. The pipe 17 leads directly into the nozzle 7 from a suitable source of air under pressure. The bowl

6 is also provided with a drain pipe 26 which leads to any suitable device for catching overflow of oil from the burner.

The amount of oil flowing to the pilot wick 11 is very small, being just sufficient to keep a low flame, and this oil flows all the time during the normal operation of the burner. When the main burner pipe 15 is open the oil will flow through it to the mixing chamber 8 and into the nozzle 7, particularly when a blast of air is admitted through the pipe 17. The mixture of air and oil passing from the nozzle will be ignited by the pilot flame and the burning of this mixture in the bowl will produce an intense heat which will soon heat the walls of the furnace. The baffle plate 12 will act to direct the flames against the walls of the furnace. The pilot flame will heat the nozzle and thus facilitate the combustion of the mixture passing through the same. As will be seen the fuel feeds by gravity so that a low grade of fuel can be used and if the oil should collect in the burner bowl due to the extinguishing of the pilot flame or for any other reason, this oil would flow through the line 26. It will be noted that the flange 10 rises from the flat bottom of the bowl 6 and is curved to provide an enclosure for the absorbent wick 11, and to support the latter immediately beneath the pilot opening 9 to catch the oil dripping therefrom. It will also be noted that the bowl 6 has a flat wall from which the nozzle 7 extends and which are formed the mixing or angle shaped passage 8 and the pilot opening 9, the latter being arranged below the nozzle 7 and opening onto the wick 11.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

A burner of the character described comprising a burner bowl, a nozzle formed in the wall of the bowl and provided with an

angle shaped passage communicating therewith and entering through the upper wall thereof, an air conducting pipe aligned with the nozzle, a fuel supply pipe connected in the angle shaped passage, a pilot pipe entering the bowl at a point below said nozzle and a flange rising from the bottom of the

bowl and provided with a chamber for absorbent material, said flange being disposed adjacent the pilot pipe passage and arranged 10 below the nozzle.

In testimony whereof I affix my signature.

CHARLES H. BEAR.
